(57) CLAIM

The ornamental design for a bench, substantially as shown and described.

DESCRIPTION

FIG. 1 is a perspective view of a bench showing my new design;

FIG. 2 is a right side view, the left side view being a mirror image thereof;

FIG. 3 is a top plan view thereof;

FIG. 4 is a front elevation view thereof;

FIG. 5 is a bottom plan view thereof; and,

FIG. 6 is a back elevation view thereof.

The broken lines showing environment in the drawings are for illustrative purposes only and form no part of the claimed design.
